UNITED STATES PATENT OFFICE.

HARRIS MOAK, OF BROOKLYN, NEW YORK.

CLOSURE FOR MILK-BOTTLES AND THE LIKE.

1,361,394.

Specification of Letters Patent.

Patented Dec. 7, 1920.

Application filed July 7, 1920. Serial No. 394,482.

To all whom it may concern:

Be it known that I, HARRIS MOAK, a citizen of the United States, residing at Brooklyn, in the county of Kings and State of New York, have invented certain new and useful Improvements in Closures for Milk-Bottles and the like, of which the following is a specification.

The object of the invention is to provide a bottle or jar closure of the type commonly used for sealing milk bottles and the like having attached thereto in improved manner extracting means for facilitating the removal of the closure from the bottle or jar in which it has been seated. The invention further aims to so construct and attach the extractor to the closure that it will be simple and inexpensive to manufacture, render easy the removal of the closure from the bottle and that it can be satisfactorily used in the capping machines commonly used to apply the closures to the bottles.

The invention consists in a closure comprising a thin disk of wood pulp or other material and an extractor device which consists of a loop of wire, the closed portion acting as a handle and lying upon the upper surface of the disk, and preferably pointing to the center of the disk, the limbs of the loop passing through the disk and extending at the bottom surface of the disk to its edge, which the ends of the limbs clasp, thus firmly fastening the extractor to the disk. The said ends of the limbs where they pass around the edge of the disk are embedded in the edge so that the latter remains practically unbroken and no opportunity is presented for leakage of the contents of the bottle.

An important feature of the invention is that by reason of the construction, as shown in the drawings, the closed handle portion does not lie over or near any portion of the fastening limbs located at the lower surface of the disk, so that the handle portion can be embedded in the upper surface of the disk to facilitate use of the closure in capping machines without affecting the holding capacity of the extractor.

By extending the limbs of the extractor on the bottom of the closure and clenching the ends around the edge of the same, not only is a secure method of attaching the extractor obtained, but commercial manufacture of the closures at a low price and on

the large scale demanded by the trade is made practical.

Referring to the drawings:

Figure 1 shows a top view of a closure embodying the invention. 60

Fig. 2 shows a view of the under surface of the said closure.

Fig. 3 shows a sectional view of the said closure.

Fig. 4 shows a perspective view of the same. 65

1 is a thin disk of wood pulp, paper or other material, 2 is the extractor device made as a loop with closed handle portion 5, 3 and 3' being the limbs of the loop, they 70 passing through the disk and extending parallel with and on the under surface of the same to the edge which their ends 4 and 4' clasp.

In practice, where closures are used in capping machines, it is necessary that an extractor device carried thereby shall not materially add to the thickness of the closure. 75 As will be seen by reference to the drawings, the handle portion 5 can be embedded 80 in the upper surface and the limbs 3 and 3' in the under surface to a degree necessary to facilitate the use of the invention in capping machines, and yet the closure is not so weakened that the extractor is liable to 85 be torn away when the closure is removed from the bottle.

It will also be seen that by extending the limbs from the point of penetration to the edge of the disk and clenching their ends 90 around the same, the strain in removing the closure from the bottle is distributed over a relatively large portion of the disk, and the strain being upward, there is practically no danger of the ends being unclenched. 95

While it is preferable that the closed handle portion 5 point to the center of the disk it is not necessary in all cases that it should do so. The loop can be made in any desired shape. 100

I claim:

1. A bottle or jar closure comprising a thin disk and an extractor device of loop form having a closed handle portion lying upon the upper surface of the disk, with 105 its limbs passing through the disk and extending at the under surface thereof to the edge of the disk, and with the ends of the limbs clasping the said edge.

2. A bottle or jar closure comprising a 110

thin disk and an extractor device of loop form, whose closed handle portion lies upon the upper surface of the disk and its limbs pass through the material of the same, said limbs extending to the edge of the disk at the under surface thereof, and clasping the edge of the disk.

3. A bottle or jar closure comprising a thin disk and an extractor device whose

handle portion lies upon the upper surface 10 of the disk, with its fastening portion passing through the same and extending upon the under surface thereof to the edge of the disk and clasping the said edge.

In testimony whereof, I affix my signature.

HARRIS MOAK.
